Lois A. Harlamert, 12 Wisteria Drive, Dayton, Ohio

Filed Nov. 4, 1964, Ser. No. 82,468

Term of patent 14 years

(Cl. D3—11)

FIG-1

FIG. 1 is a perspective view of a mitten showing my new design, with the dot-dash line showing of arms broken away being for illustrative purposes only;

FIG. 2 is a plan view of my design, with the opposite side being substantially identical; and

FIG. 3 is a side view thereof.

This application is a continuation-in-part of Serial No. D. 76,018, filed July 29, 1963, and now abandoned.

I claim:

The ornamental design for a mitten, substantially as shown and described.
